United States Patent Office

Des. 189,519
Patented Jan. 3, 1961

189,519

SWEATER

Hans Boepple, 1410 Broadway, New York, N.Y.

Filed May 23, 1960, Ser. No. 60,695

Term of patent 14 years

(Cl. D3—4)

I claim:

The ornamental design for a sweater, substantially as shown.
